UNITED STATES PATENT OFFICE

109,140

DESIGN FOR A COMBINED ERASER AND PENCIL TIP

David Juelss, Brooklyn, N. Y., assignor to American Lead Pencil Company, Hoboken, N. J., a corporation of New York

Application February 3, 1938, Serial No. 74,816

Term of patent 14 years

To all whom it may concern:

Be it known that I, David Juelss, a citizen of the United States, residing at 2202 64th Street, Brooklyn, in the county of Kings and State of New York, have invented a new, original, and ornamental Design for a Combined Eraser and Pencil Tip, of which the following is a specification, reference being had to the accompanying drawing, forming part thereof.

Figure 1 is a side elevational view, Figure 2 is a front elevational view, and Figure 3 is a plan view of a combined eraser and pencil tip showing my new design.

I claim:

The ornamental design for a combined eraser and pencil tip, substantially as shown.

DAVID JUELSS.
